DESIGN FOR A GLASS HOLDER ATTACHMENT FOR TABLE EDGE

Ted E. Foulke, Lyndhurst, Ohio

Application May 10, 1947, Serial No. 138,978

Term of patent 3½ years

(Cl. D44—29)

To all whom it may concern:

Be it known that I, Ted E. Foulke, a citizen of the United States, and a resident of Lyndhurst, Cuyahoga County, Ohio, have invented a new, original, and ornamental Design for a Glass Holder Attachment for Table Edge, of which the following is a specification, reference being had to the accompanying drawings, forming a part thereof.

In the drawings,

Fig. 1 is a perspective view of a glass holder attachment for table edge, showing my new design; Fig. 2 is a rear elevational view; and Fig. 3 is a bottom plan view thereof.

I claim:

The ornamental design for a glass holder attachment for table edge, as shown.

TED E. FOULKE.
